CONVEYOR TROLLEY HANGER

Morton A. Weiss, Springfield, and Bernard S. Speckhart, Short Hills, N.J., assignors to White Machine Co., Kenilworth, N.J., a corporation of New Jersey

Filed Apr. 18, 1968, Ser. No. 11,521

Term of patent 14 years

Int. Cl. D15—99; D8—03
U.S. Cl. D55—1

FIG. 1

FIG. 2

FIG. 3

FIG. 4

FIG. 5

FIG. 6

FIG. 1 is a perspective view of a conveyor trolley hanger showing our new design;

FIG. 2 is a top plan view thereof;

FIG. 3 is a front elevational view thereof;

FIG. 4 is a side elevational view thereof, the opposite side being a mirror image of the side shown;

FIG. 5 is a rear elevational view thereof; and

FIG. 6 is a bottom plan view.

We claim:

The ornamental design for a conveyor trolley hanger, as shown and described.
